SHIP RAISING RIGGING

Steve Minio, Carteret, N. J.

Application May 2, 1935, Serial No. 19,497

1 Claim. (Cl. 114—52)

The invention relates to salvaging equipment for watercraft and more especially to a ship raising rigging.

The primary object of the invention is the provision of a rigging of this character, wherein through the use of the same a sunken vessel, such as a ship, submarine or the like craft may be conveniently located for purposes of enabling the salvaging of the cargo thereof or if such vessel is to be raised the same can be, the rigging being of novel construction and is convenient for the purposes intended thereof.

Another object of the invention is the provision of a rigging of this character, wherein the same is constructed for carriage upon a ship and when the latter sinks it will enable a wrecking craft to conveniently locate the sunken ship either for the raising thereof or for the salvaging of its load.

A further object of the invention is the provision of a rigging of this character, which is comparatively simple in its construction, thoroughly reliable and efficient for the purposes intended thereof, possessing strength and durability, convenient for handling and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is an elevation diagrammatically illustrating the rigging constructed in accordance with the invention applied to a sunken vessel or ship and a rigging craft in association with the rigging.

Figure 2 is a fragmentary side elevation thereof. Figure 3 is an enlarged sectional view on the line 3—3 of Figure 1 looking in the direction of the arrows.

Figure 4 is an enlarged sectional view on the line 4—4 of Figure 2 looking in the direction of the arrows.

Figure 5 is a fragmentary sectional view similar to Figure 4 showing the parts in a changed position.

Figure 6 is a fragmentary transverse sectional view through a releasable coupling of the rigging.

Figure 7 is a side elevation of a modified form of pontoon.

Figure 8 is a fragmentary side elevation of a ship showing the pontoon disclosed in Figure 7

at rest upon the ship with a lashing to deck supports therefor.

Figure 9 is an enlarged fragmentary side elevation partly in section of the pontoon shown in Figure 7.

Figure 10 is a sectional view on the line 10—10 of Figure 9 looking in the direction of the arrows.

Figure 11 is a vertical transverse sectional view thereof showing a modified form of attaching the pontoon to a deck support.

Figure 12 is a fragmentary elevation of a carrier chain for the pontoon.

Figure 13 is a sectional view on the line 13—13 of Figure 12 looking in the direction of the arrows.

Similar reference characters indicate corresponding parts throughout the several views in the drawings.

Referring to the drawings in detail, the rigging comprises several tandem pontoons, each including a pair of buoyant bodies 10 which are spaced 20 the required distance from each other and are united in this spaced relation through the medium of connecting bars 11 and 12, respectively, which are arranged in horizontally spaced relation to each other. In each buoyant body 10 is provided 25 a chamber 13 in which is arranged a rotatable reel 14 having attached thereto a cable 15 which is adapted to be wound on and unwound from the said reel 14, the arbor or axle 16 for the reel 14 being adapted to have connected thereto a hand 30 crank 17 for the rotation of the said reel by hand.

The cable 15 is adapted to play through an eye 18 provided in the bottom of the buoyant body 10 and the cables of the tandem of both bodies 10 are connected to pivotal link ratchet chains 35 18' at 19. These chains 18' are connected at 20 with anchoring brackets 21 made fast externally to the hull or the ship's body 22 at a point adjacent to the water line of the same and such chains are of a length to extend at least thirty feet above 40 the highest point of the ship's body.

It is preferable to have a pair of tandem buoyant bodies 10 arranged at each side of the ship's body and according to the size of the latter a plurality of these may be at each side thereof. 45 Upon the deck of the ship's body are supports 23 for the said pontoons which normally are at rest thereon and for carriage by the ship. In one instance the pontoons are lashed to these supports 23 and when the ship is about to sink the 50 said pontoons are freed of the supports 23 and by buoyancy they will ride the body of water at the surface thereof, the cables 15 being automatically played out from the reels 14 during the sinking of the vessel so that the said pon- 55

toons shall remain afloat at the water surface. Each buoyant body 10 has a conical cap 24 and the same is preferably finished for reflecting purposes so as to render the pontoons visible above 5 the water surface for enabling the location of the sunken craft by a wrecking craft travelling the water body.

The wrecking craft 25 is adapted to have on-board tanks 26 each being provided with a 10 leasable guide coupling 27 the releasing function being had by a screw bolt 28 therewith. The coupling 27 of the tank 26 permits attachment of the latter with a cable 15 and the guiding of this tank in descent and ascent thereon within 15 a body of water. Each chain 18' carries at the respective links thereof spring tension ratchet dogs 29 arranged throughout the length of said chain so that the screw bolt 28 of the coupling 27 will ratchet over these dogs 29 on the descent 20 of the tank 26 when the coupling rides onto the chain 18' but said dogs 29 will latch the coupling 27 from reverse upward movement of the tank 26. The descent of each tank 26 in the body of the water is had by filling such tank with water 25 contents as at 30, the attachment of the tank with a cable 15 being had by the wrecking crew on the craft 25. Each tank 26 has provided in one side thereof an outlet return check valve 31 and also attachable to the tank for communication therewith is an air flow tube or pipe 32 for introducing under pressure air within the tank 30 for expelling the water contents thereof which will be driven through the check valve 31, the latter excluding the return of the water to 35 the tank. When the water contents is relieved within the tank 26 the same becomes buoyant and such water contents is driven from the tank when the latter has descended by the weight of the water therein into the body of water in close- 40 ness to the ship's body when sunken within the body of the water so that when the water contents is expelled from the tank 26 its buoyancy will function to raise the sunken vessel. The air flow tubes or pipes 32 lead from the wrecking craft 25 and are in conjunction with a suitable air compressor (not shown) as located upon such wrecking craft so that air under pressure may be conveyed by these tubes or pipes for the purposes stated.

Each tank 26 has interiorly thereof a weight 45 33 which functions to have the tank 26 descend in the position as shown in Figure 4 of the drawings to one side of the cable 15 and chains 18' when water is contained within the tank. Then 50 when the water is expelled from the tank 26 the latter turns to have the point of pull on the chain 18' at the vertical center and at the lowermost point of such tank as is clearly shown in Figure 5 of the drawings.

In Figures 7 to 11 of the drawings there is 55 shown a modified form of pontoon wherein it includes an intermediate cork filled buoyant body 34 having at opposite ends the casings 35 each having a winding and unwinding reel 36 to which is connected the cable 37 similar or corresponding to the cable 15. This body 34 carries the upwardly tapered reflector rib or crown 35' corresponding to the crowning cap 24.

In Figure 11 of the drawings there is shown a still further modification wherein this pontoon having the body 34 at its front has fitted therewith a steel plate 38 while the deck supports 39 corresponding to the supports 23 are each fitted 5 with an electrically energized magnet 40 coacting with the plate 38 to hold fast the pontoons which rest upon the ship's body. Now when the electric energy to the magnet 40 is shut off the pontoon having the plate 38 will be instantly 10 released for the overboard floating of such pontoon coincident with the sinking of the ship.

When the ship has sunken and the wrecking craft 25 arrives at the point where the ship has sunken these tanks 26 are normally devoid of 15 water content or air and the same are placed overboard for attachment to the cables 15 or 37 and thereafter the said tanks 26 are filled with water so that the same will descend and ratchet the chains 18' until the tanks arrive adjacent to 20 the sunken ship, the pipes or tubes 32 playing out from the craft 25 during the descent of the tank so that when these tanks arrive adjacent to the ship the water contents of such tanks can be expelled therefrom to render the same buoyant 25 for the lifting of the sunken vessel.

Of course, if it is not desired to raise the sunken vessel or ship the locating of such may be had by the pontoons so that salvaging of the load of the vessel or ship may be carried forth by 30 the wrecking crew of the craft 25, the locating of the sunken vessel or ship being accomplished in a manner as before indicated.

It is desirable to have located on the pontoons suitable handholds 41 so that persons overboard 35 can obtain a grip on these for sustaining themselves afloat and avoid drowning. These handholds can be in the nature of belts whereby they can be fastened about the body of a person.

The handholds 41 are located at opposite sides 40 and ends of the pontoons 34. It is, of course, understood that suitable grips may be provided on the pontoons 10 equivalent to the handholds referred to.

What is claimed is:

A rigging of the character described comprising a pontoon, means for releasably fixing the pontoon to a ship, link chains carried by the ship and having flexible let-out and take-up connections with the pontoon, means in the pontoon for 50 the letting out and taking up of said connections, a tank for receiving air and water, means for admitting water to the tank for the sinking of the latter in a body of water, means for admitting air to said tank for expelling water therefrom to render said tank buoyant for its rise to the surface of the water, a detachable coupling on the tank and slidably connecting the latter with the chains, and ratchet dogs pivoted to the 55 respective links of said chains throughout the same and cooperating with the detachable coupling for allowing free movement of said tank upon the chains in one direction and the intermediate latching of such tank against movement in the reverse direction throughout the extent 60 of the chains.

STEVE MINIO.
